UNITED STATES PATENT OFFICE.

ORMOND EDGAR WALL, OF HONOLULU, TERRITORY OF HAWAII.

TOY.

1,275,331.

Specification of Letters Patent. Patented Aug. 13, 1918.

Application filed July 31, 1917. Serial No. 183,724.

To all whom it may concern:

Be it known that I, ORMOND EDGAR WALL, a citizen of the United States, and a resident of Honolulu, in the Territory of Hawaii, 5 have invented a new and useful Improvement of Toys, of which the following is a specification.

My invention relates to improvements in toys, and it consists in the combinations, 10 constructions and arrangements herein described and claimed.

An object of my invention is to provide a toy having mounted thereon a number of guns for firing projectiles, with means 15 for actuating the guns successively, to fire the projectiles one after the other.

A further object of my invention is to provide a device of the type described, which is of a very simple nature, consists of few 20 parts, and hence is not easily liable to be put out of order.

Further objects and advantages will appear in the following specifications and the novel features of the invention will be particularly pointed out in the appended claims. 25

My invention is illustrated in the accompanying drawings forming part of this application, in which:

Figure 1 is a perspective view of a boat 30 equipped with toy guns which are actuated by the mechanism which forms the subject of the present invention.

Fig. 2 is a diagrammatical view showing the manner in which the projectile is held 35 in the gun.

Fig. 3 is a view showing the manner in which the release of the projectile is effected.

In carrying out my invention I may make 40 use of any toy which has toy guns mounted thereon, as for instance, a boat, a fort, an armored car, etc. In the present instance, I have shown a boat 1, which is provided with turrets 2, having guns 3 projecting therefrom. Other guns may project from the 45 sides of the boat.

Each of these guns consists of a cylinder 3^a; see Fig. 2, arranged to receive a projectile 4. The latter may be of any suitable 50 material such as wood, metal, etc., and is provided with a groove 5. A slidable locking pin 6 is arranged to enter the groove 5. A bell-crank lever 7 is pivoted at 8, and one end of the lever is pivotally connected with 55 the slidable pin 6, the opposite end being connected by means of a link 9 with a lever

10 which is pivoted at 11. A spring 12 normally holds this link and lever connection in such position as to force the slidable pin 6 inwardly into the groove 5. A slidable 60 pin 13 is disposed with one end adjacent to the lever 11, the opposite end being arranged to be engaged by an expanding spring in the manner hereinafter described.

At any suitable point within the vessel is 65 secured a coiled spring 14, this spring being fastened at one end to a post 15, and at the other end to a rotatable spindle 16, which has connection with a winding key 17.

Disposed about this spring are other slidable pins 13^x and 13^y, similar to the slidable pin 13, these slidable pins being in engagement with levers 10^x and 10^y similar to the lever 10; these levers lead to other guns similar to that shown at 3^a. There 75 may be as many of these guns with link and lever connections as desired.

From the foregoing description of the various parts of the device the operation thereof may be readily understood. 80

The guns are loaded by forcing the projectile 4 inwardly against the tension of the spring 18, the end of the projectile being beveled as shown at 4^a, the locking pin 6 is forced outwardly, the pin entering the 85 groove 5. A collar 6^x on the pin limits the movement. Each of the guns is loaded in precisely the same manner.

The spring 14 which was previously wound and kept from turning, either by holding with the hands or by the provision of any suitable locking mechanism, not shown is now released. As the spring 14 unwinds, the diameter of the spring gradually increases, as shown in Fig. 13. The pins 13, 90 13^x, and 13^y, are set at different distances from the center of the spring, and as the spring comes in contact with these pins, successively, it forces each one outwardly, and through the medium of the link and lever 95 connection withdraws the locking pin 6, so that the spring is free to force the projectile from the gun. Thus the guns are fired in succession. The link and lever connection is designed to have sufficient play so that 100 as the spring keeps on expanding, the movement of the pins 13 will have no other effect.

I have shown the link and lever connection together with the slidable pin as being one form which may be used, but it is obvious 110 that other forms of the device might be used without departing from the spirit of the in-

vention; for instance, the spring might engage the levers 11 directly and operate them in succession.

In the drawing I have illustrated a construction in which the guns are provided with projectiles, but it will be understood that the guns may be provided with caps for exploding, or other sound-producing devices which may be actuated in succession 10 by the uncoiling of the spring.

I claim:

1. In a toy, a base, a plurality of movable devices mounted upon said base, means for normally locking said movable devices in 15 position, and automatic means for releasing the locking means successively, said means comprising a coiled spring and means engaged by the spring when uncoiling for withdrawing the locking mechanism.
2. In a toy, a base, a plurality of guns carried thereby, and automatic means for firing the guns successively, said means comprising a coiled spring and means engaged by the spring when uncoiling for operating 25 the firing means.

3. In a toy, a base, a plurality of guns carried thereby, each of said guns being provided with a spring, a projectile for each gun, arranged to engage the spring, and to compress the latter, a locking pin arranged to engage the projectile, a link and lever connection for each locking pin, and a coiled spring arranged to actuate each of the link and lever connections in succession, causing the release of the locking pin and the firing 30 35 of the projectile.

4. In a toy, a base, a plurality of guns carried thereby, each of said guns being provided with a spring, a projectile for each gun arranged to engage the spring and to compress the latter, a locking pin arranged to engage the projectile, a link and lever connection for each locking pin, and a coiled spring arranged to actuate each of the link and lever connections in succession, causing 40 45 the release of the locking pin and the firing of the projectile, said link and lever connections being disposed at different distances from the center of the spring.

ORMOND EDGAR WALL.
